LIQUID FUEL CONTAINER FOR BOATS OR THE LIKE

William F. Voelz, Jr., Thiensville, Wis., assignor to The Alva T. Smith Company, Milwaukee, Wis., a corporation of Wisconsin

Filed June 15, 1959, Ser. No. 56,351

Term of patent 14 years

(Cl. D58—17)

Figure 1 is a perspective view of a liquid fuel container for boats or the like embodying my new design; Figure 2 is a side elevational view thereof; and Figure 3 is an end elevation thereof.

I claim:

The ornamental design for a liquid fuel container for boats or the like, substantially as shown.
